UNITED STATES PATENT OFFICE.

FRED SWAN, OF MARIETTA, OHIO.

SOLID-WEDGE UNDERREAMER.

Application filed July 3, 1923. Serial No. 649,341.

To all whom it may concern:

Be it known that I, FRED SWAN, a citizen of the United States, residing at Marietta, in the county of Washington and State of Ohio, have invented certain new and useful Improvements in Solid-Wedge Underreamers, of which the following is a specification, reference being had to the accompanying drawings, forming a part thereof.

10 My invention relates to under-reamers for use in drilled wells for the purpose of enlarging a hole drilled below casing and has for its object to provide a construction of under-reamer which will be particularly 15 adapted for use in wells of small diameter.

The Swan under-reamer of the type shown in U. S. patents to John C. Swan, Nos. 683-352, dated Sept. 24, 1901, and 979,106, dated Dec. 20, 1910, is satisfactory for use in wells 20 of diameter from 5 inches up and will do effective work in wells of less diameter but for use in wells of a diameter of 4 inches or less the reaming bits or cutters necessarily have to be made of small size and in this 25 type of under-reamer as well as in all other types of under-reamers with which I am familiar, it is difficult to produce cutters of the small size required which can be depended on to have the strength necessary 30 to stand up under the conditions to which they are subjected in the operation of underreaming. This difficulty is further increased by the necessity of using in very deep wells casing of increased thickness to withstand the 35 water pressure at great depths, the increased thickness of the casing necessarily reducing the interior diameter of the casing through which the drill must pass and increasing the difference in diameter between the hole 40 drilled below the casing and the hole to which it must be enlarged by the under-reamer to permit the casing to be lowered. The increased amount of work thus required to be done by the under-reamer while requiring some changes in proportion of the operating parts in the under-reamers for use 45 in wells of 5 inches or more in diameter is not particularly serious as regards such under-reamers but in under-reamers for the wells of smaller diameter increases difficulties which were already such that manufacturers of under-reamers which are effective for wells of larger diameter are unable to furnish under-reamers for wells of 4 inches 50 diameter which will do satisfactory work.

The present invention is designed and in-

tended to provide an under-reamer in which solid cutters will be backed when in operating position, by a solid wedge and the movement longitudinal of the under-reamer body 60 required in the movement of the cutters from collapsed to expanded position will be greatly reduced, even though more than usual expansion is required so that the strength necessary for effective work may be secured 65 however small in diameter the under-reamers may be.

With the object above indicated, and other objects hereinafter explained in view, my invention consists in the construction and 70 combination of elements hereinafter described and claimed.

Referring to the drawings:

Figure 1 is a side view of an under-reamer embodying my invention, the under-reamer being shown in position to be inserted in the well casing, the reaming bits or cutters being shown in collapsed position.

Fig. 2 is a bottom end view of the under-reamer shown in Fig. 1.

Fig. 3 is a front view of the under-reamer shown in Fig. 1, the under-reamer being shown in the well casing.

Fig. 4 is a cross sectional view on line 4-4 of Fig. 3.

Fig. 5 is a front view of the under-reamer with the reaming bits or cutters in expanded position in the well hole, below the casing.

Fig. 6 is a side view of the under-reamer with the reaming bits or cutters in expanded position.

Fig. 7 is a bottom plan view of the under-reamer shown in Fig. 6.

Fig. 8 is a top plan view of the under-reamer body.

Fig. 9 is a side view of one of the reaming bits or cutters.

Fig. 10 is a bottom end view of the reaming bit or cutter shown in Fig. 7.

Fig. 11 is a top plan view of the same.

Fig. 12 is a side view of the rod by which the reaming bits or cutters are drawn up into expanded position, and Fig. 13 is an end view of the same.

Fig. 14 shows, in side and end views, the pin on which the shanks of the reaming bits or cutters are pivoted.

Fig. 15 shows inside and edge view, the nut for end of the pin shown in Fig. 14, and

Fig. 16 is a detail view of the pin 36.

In the drawings 1 indicates the under-

reamer body having at its lower end a central wedge 2 rectangular in cross section, except that it is cut away on each side to receive the shank of one of the cutters, having at its lower end opposite inclined faces 3 at an angle of about 45 degrees. From the upper ends of these inclined faces the main faces 4 of the wedge extend upward and outward at a slight angle to the axial line of the under-reamer body to abutments 6, the lower faces of which are inclined outward and downward at a slight angle to a plane at right angles to the axial line of the under-reamer body. The sides 7 of the wedge are flat and parallel with the axial line of the under-reamer body. In the same planes with these sides 7 are formed recesses 8 extending upward from the abutments 6, the sides 9 and 10 converging from the abutments upward and terminating in arcs 11 which form a semicircular end for the recess.

The under-reamer body is centrally bored from its upper end to a point in line with the abutments 6. In line with the lower portions of this central bore 12 is formed a slot 13 extending through the under-reamer body at right angles to the planes of the recesses 8. This slot 13 extends longitudinally of the under-reamer body from a point in line with the abutments 6 to a point in line with the upper ends of the recesses 8. The central bore is enlarged, as shown at 14, from the upper end of the under-reamer body down to a short distance above the line of the upper ends of the recesses 8, this enlargement terminating in an annular shoulder 15. At its extreme upper end the central bore is enlarged to form the tapered screw threaded coupling socket 16.

Into the lower portion of the central bore extends a rod 17 having holes 18 and 19 extending through it at right angles to its axis and having a head 20 at its upper end, of a diameter adapted to fit the interior of the enlargement 14. Between this head 20 and the annular shoulder 15 surrounding the upper portion of the rod is a coiled spring 21 which tends to force the rod upward. Through the hole 18 of the rod 17 extends a pin 22 which extends through the slots 13 into the recesses 8 and has secured in its ends within the recesses the shanks 55 of the reaming bits or cutters.

The reaming bits or cutters are two in number, the two being exactly alike. Each comprises a solid body portion 25 having its lower face so formed that when in expanded position it will be in a plane substantially at right angles to the axial line of the under-reamer, this lower face having its outer edge formed on substantially the arc of a circle having the diameter of the hole to which the hole below casing is to

be enlarged. The sides 26 of the body portion are flat and parallel. From the lower edge the outer face of the body portion 25 tapers upward and inward. The upper ends of the body portion is formed in an angle which corresponds to the angle of the lower face of the abutment 6. From its outer edge inward the thickness of the body portion 25 is such that when the body portions of the two cutters are brought together in collapsed position they will readily pass into the well casing.

The rear face of the body portion 25 is provided near its sides 26 with inwardly extending wings 27 and 28 which extend upward beyond the upper face of the body portion to form shanks 29 and 30, having near their ends holes 31 to receive the ends of the pin 22. The wing 27 and shank 29 of one of the cutters fits against a side 7 of the wedge and against the bottom of a recess 8 and the wing 28 and shank 30 of the other cutter fits against the outer face of the wing 27 and shank 29 of the first cutter, the holes 31 of the shanks being in line. The upper ends of the shanks are rounded off to correspond with the rounded upper ends of the recess 8, and the outer edges of the shanks are so formed that when the cutters are in expanded position these edges are in line with and nearly in contact with the sides 9 and 10 of the recess 8.

In order to permit the under-reamers to pass through the well casing the cutters are drawn downward until the upper faces of the body portions 25 are below the lower end of the wedge and the rear faces of these body portions 25 are nearly in contact. For convenience in drawing the cutters down to this position they are each provided in their outer face with a recess 35 for inserting the hooked end of a suitable tool. In thus drawing the cutters down to the position indicated, the pin 22 is drawn down with them and the rod 17 is drawn down with the pin against the resistance of the spring 21. In order to hold the cutters in the collapsed position a pin 36 is passed through the hole 19 when the hole 19 is below the upper end of the slot 13, and by its engagement with the upper end of this slot prevents the rod 17 from being drawn up by the spring.

When the cutters have been inserted within the casing the pin 36 is to be withdrawn and the under-reamer may be lowered through the casing. As soon as the body portions 25 pass below the lower end of the well casing the spring 21 acting in the rod 17 draws the cutters upward. The upper rear edges of the body portions 25 ride upward and outward on the inclined faces 3 of the wedge, causing the cutters to swing outward turning on the pin 22. The inner faces of the body portions 25 then slide up-

ward on the slightly tapered faces 4 of the wedge until their upper ends are against the abutments 6. As these upper ends of the cutter bodies come in contact with the abutments the outer edges of the shanks 29 and 30 come in contact or nearly in contact with the edge walls 9 and 10 of the recesses 8. The reaming bits or cutters are thus in expanded position, being held against inward

movement by the contact of their rear faces with the solid wedge 2; they are held against upward movement by the contact of their upper rear edges with the abutments 6 and are held against outward movement by the contact of the shanks 29 and 30 with the side walls 9 and 10. The cutters are thus firmly held from movement in any direction except downward and are yieldingly held against downward movement by the spring 21.

20 The pin 22 has a head 40 formed at one end and at the other end is reduced in diameter as shown at 41, the reduced portion being screwthreaded to receive a nut 42 which when screwed on to the reduced portion bears against a shoulder 43 so that it cannot be forced against the shanks of the cutters so as to cause them to bend against the bottoms of the recesses. A cotter pin 44 serves to prevent nut 42 from being accidentally unscrewed.

25 The pin 36 is cylindrical from the end at which it carries the ring 45 to a point 46 midway between its ends, and from this point to its free end it is tapered. When in place as shown in Fig. 1, the point 46 will be approximately in line with the center of the rod 17. As soon as the pin is pulled outward until the point 46 is out of the rod 17 the action of the spring causes the wall of 30 the hole 19 to act upon the tapered portion of the pin to facilitate its withdrawal. The ring 45 is preferably made of a diameter slightly greater than the interior diameter of the casing in which the under-reamer is 35 to be used, so that the pin cannot be dropped into the casing. It will, of course, be understood that the pin 36 is used only when the under-reamer is out of the casing to lock the cutters in collapsed position.

40 In order to allow for different weights of casing, that is casing for the same size of well hole but differing in thickness and consequently differing in interior diameter, the upper ends of the cutters are turned to an arc of a circle of less diameter than that of the inside diameter of the casing, and the outer faces of the cutters are tapered slightly from their upper ends to their cutting edges.

45 The upper faces 4 of the wedge which serve as bearings for the rear faces of the cutter bodies 25, are of substantially the same length as the cutter bodies, so that when the cutters are in expanded position the lower end of the wedge is only slightly

below the lower ends of the cutter bodies. The slot 13 is wholly above the upper end of the wedge, and the wedge is solid from the line of the abutments to its lower end, and when the cutters are in expanded position 50 the cutter bodies with the solid wedge between them forms practically a solid mass of metal from the cutting edge of one cutter to the cutting edge of the other.

Having thus described my invention what I claim is:

1. In an under-reamer, a reamer body having at its lower end a downwardly extending solid wedge and having abutments at the upper end of the wedge, oppositely arranged cutters having solid bodies having their rear faces adapted to bear against the faces of the wedge and having shanks extending upward from their bodies, the shanks of the two cutters overlapping one 55 on the other and being pivotally connected, and means engaging the shanks for drawing the cutters upward to bring their upper ends against the abutments.

2. In an under reamer, a reamer body having at its lower end a downwardly extending solid wedge and having abutments at the upper end of the wedge, oppositely arranged cutters having solid bodies having their rear faces adapted to bear against the faces of the wedge and having shanks extending upward from their bodies, the shanks of the two cutters overlapping one on the other and being pivotally connected, and means engaging the shanks for drawing the cutters upward to bring their upper ends against the abutments, and means engaging the shanks to hold the cutter bodies against the faces of the wedge.

3. In an under-reamer, a reamer body having at its lower end a downwardly extending solid wedge and having abutments at the upper end of the wedge, oppositely arranged cutters having solid bodies having their rear faces adapted to bear against the faces of the wedge and having shanks extending upward from their bodies, the shanks of the two cutters being pivotally connected, and means wholly above the line of the abutments for engaging the shanks for drawing the cutters upward to bring their upper ends against the abutments.

4. In an under-reamer, a reamer body having centrally of its lower end a downwardly extending solid imperforate wedge having upper faces inclined at a slight angle to the axial line of the reamer body and adapted to serve as bearing surfaces for the rear faces of solid cutter bodies, abutments at the upper ends of said upper faces of the wedge, cutters having solid bodies having their rear faces adapted to bear against said upper faces of the wedge and having shanks extending upward above the line of the abutments, and means above the line of the abut-

ments for engaging the shanks to hold the cutter bodies against the faces of the wedge.

5. In an under-reamer, a reamer body having centrally of its lower end a downwardly extending solid imperforate wedge having upper faces inclined at a slight angle to the axial line of the reamer body and adapted to serve as bearing surfaces for the rear faces of solid cutter bodies, abutments 10 at the upper ends of said upper faces of the wedge, cutters having solid bodies having their rear faces adapted to bear against said upper faces of the wedge and having shanks extending upward above the line of the abutments, means above the line of the abutments for engaging the shanks to hold the cutter bodies against the faces of the wedge, and means for drawing the cutter bodies upward on the faces of the wedge.

20 6. In an under-reamer, a reamer body having centrally of its lower end a downwardly extending solid imperforate wedge having upper faces inclined at a slight angle to the axial line of the reamer body and 25 adapted to serve as bearing surfaces for the rear faces of solid cutter bodies, abutments at the upper ends of said upper faces of the wedge, oppositely arranged cutters having solid bodies having their rear faces adapted 30 to bear against said upper faces of the wedge and having shanks extending upward above the line of the abutments, the shanks of the oppositely arranged cutters being pivoted together, means above the line of the abutments for engaging the shanks to hold the cutter bodies against the faces of the wedge, and means for drawing the cutter bodies upward on the wedge.

7. In an under-reamer, a reamer body having centrally of its lower end a downwardly extending solid imperforate wedge having upper faces inclined at a slight angle to the axial line of the reamer body and lower faces at a materially greater angle to said axial 45 line, the upper faces being adapted to serve as bearing surfaces for the rear faces of the bodies of the cutters and the lower faces being adapted to separate the cutter bodies as they are drawn upward from collapsed 50 position, abutments at the upper ends of the upper faces of the wedge, and cutters having solid bodies having their rear faces of substantially the same length as the upper faces of the wedge and movable thereon, and having their upper ends adapted to fit 55 against said abutments, and means for drawing the cutters upward into contact with said abutments adapted to permit the upper ends of the cutter bodies to pass below the lower end of the wedge.

60 8. In an under-reamer, a reamer body having centrally of its lower end a downwardly extending solid imperforate wedge having upper faces inclined at a slight angle to the axial line of the reamer body and lower faces

at a materially greater angle to said axial line, the upper faces being adapted to serve as bearing surfaces for the rear faces of the bodies of the cutters and the lower face being adapted to separate the cutter bodies as they are drawn upward from collapsed position, abutments at the upper ends of the upper faces of the wedge, and cutters having solid bodies having their rear faces of substantially the same length as the upper faces of the wedge and movable thereon, and having the upper ends adapted to fit against said abutments, and means for drawing the cutters upward into contact with said abutments adapted to permit the upper ends of the cutter bodies to pass below the lower end of the wedge, comprising shanks extending upward from the cutter bodies and means located wholly above the line of the abutments engaging said shanks.

90 9. In an under-reamer, a reamer body having centrally of its lower end a downwardly extending solid imperforate wedge having upper faces inclined at a slight angle to the axial line of the reamer body and lower faces at a materially greater angle to said axial line, the upper faces being adapted to serve as bearing surfaces for the rear faces of the bodies of the cutters and the lower faces being adapted to separate the cutter bodies as they are drawn upward from collapsed position, abutments at the upper ends of the upper faces of the wedge, and cutters having solid bodies having their rear faces of substantially the same length as the upper faces of the wedge and movable thereon, and having the upper ends adapted to fit against said abutments, and means for drawing the cutters upward into contact with said abutments adapted to permit the upper ends of the cutter bodies to pass below the lower end of the wedge, comprising shanks extending upward from the cutter bodies, a slot 95 extending through the reamer body in line with its axis and wholly above the line of the abutments, a pin engaging the shanks and movable in said slot and means for forcing the pin upward.

10. In an under-reamer, a reamer body having centrally of its lower end a downwardly extending solid imperforate wedge having upper faces inclined at a slight angle to the axial line of the reamer body and lower faces at a materially greater angle to said axial line, the upper faces being adapted to form bearing surfaces for the rear faces of the bodies of the cutters and the lower faces being adapted to separate the cutter bodies as they are drawn upward from collapsed position, abutments at the upper ends of the upper faces of the wedge, and cutters having solid bodies having their rear faces of substantially the same length as the upper faces of the wedge and movable thereon, and having the upper ends adapted to fit 115

against said abutments, and means for drawing the cutters upward into contact with said abutments adapted to permit the upper ends of the cutter bodies to pass below the 5 lower end of the wedge, comprising shanks extending upward from the cutter bodies, a slot extending through the reamer body in line with its axis and wholly above the line of the abutments, a pin engaging the shanks 10 and movable in said slot and a spring within the reamer body for forcing the pin upward.

11. A reaming bit or cutter for underreamers having a solid body, wings extending rearward from said body parallel with 15 its sides one of said wings having its outer face in line with one of the sides and the other wing having its outer face spaced inward from the line of the other side a distance corresponding to the thickness of the 20 other wing so that when two cutters are placed back to back one wing of each cutter will have its inner face against the outer face of a wing of the other cutter, in combination with a solid wedge adapted to fill 25 the space between the wings of the cutter and serve as a support for the cutter bodies to sustain them against inward movement, the wings being extended upward and rear-

ward above the upper ends of the cutter bodies to form shanks adapted to be pivotally secured together at their upper ends. 30

12. A reaming bit or cutter for underreamers having a solid body, wings extending rearward from said body parallel with its sides one of said wings having its outer 35 face in line with one of the sides and the other wing having its outer face spaced inward from the line of the other side a distance corresponding to the thickness of the other wing so that when two cutters are 40 placed back to back one wing of each cutter will have its inner face against the outer face of a wing of the other cutter, in combination with a solid wedge adapted to fill 45 the space between the wings of the cutter and serve as a support for the cutter bodies to sustain them against inward movement, the wings being extended upward and rearward above the upper ends of the cutter bodies to form shanks, means for pivotally securing 50 the upper ends of the shanks together and means for restricting the outward swing of the shanks on the pivot.

In testimony whereof I hereunto affix my signature.

FRED SWAN.
